(57) **CLAIM**

We claim the ornamental design for an emergency signaling device, as shown and described.

DESCRIPTION

FIG. 1 is a top perspective view of my new design comprising an emergency signaling device;

FIG. 2 is a left view of the emergency signaling device of FIG. 1;

FIG. 3 is a back side view of the emergency signaling device of FIG. 1;

FIG. 4 is a front view of the emergency signaling device of FIG. 1;

FIG. 5 is a right side view of the emergency signaling device of FIG. 1;

FIG. 6 is a top side view of the emergency signaling device of FIG. 1; and,

FIG. 7 is a bottom view of the emergency signaling device of FIG. 1.
